(57) **CLAIM**

The ornamental design for a grid pattern for sink grids and rinse baskets, as shown and described.

DESCRIPTION

FIG. 1 is a perspective view taken from the top, front, and right side of a grid pattern for sink grids and rinse baskets showing our new design;

FIG. 2 is a top plan view of the grid pattern for sink grids and rinse baskets shown in FIG. 1;

FIG. 3 is a bottom view of the grid pattern for sink grids and rinse baskets shown in FIG. 1;

FIG. 4 is a front elevational view of the grid pattern for sink grids and rinse baskets shown in FIG. 1;

FIG. 5 is a rear elevational view of the grid pattern for sink grids and rinse baskets shown in FIG. 1;

FIG. 6 is a left elevational side view of the grid pattern for sink grids and rinse baskets shown in FIG. 1;

FIG. 7 is a right elevational side view of the grid pattern for sink grids and rinse baskets shown in FIG. 1;

FIG. 8 is a perspective view taken from the top, front, and right side of another embodiment of a grid pattern for sink grids and rinse baskets showing my new design;

FIG. 9 is a top plan view of the grid pattern for sink grids and rinse baskets shown in FIG. 8;

FIG. 10 is a bottom view of the grid pattern for sink grids and rinse baskets shown in FIG. 8;

FIG. 11 is a front elevational view of the grid pattern for sink grids and rinse baskets shown in FIG. 8;

FIG. 12 is a rear elevational view of the grid pattern for sink grids and rinse baskets shown in FIG. 8;

FIG. 13 is a left elevational side view of the grid pattern for sink grids and rinse baskets shown in FIG. 8;

FIG. 14 is a right elevational side view of the grid pattern for sink grids and rinse baskets shown in FIG. 8;

FIG. 15 is a perspective view taken from the top, front, and right side of another embodiment of a grid pattern for sink grids and rinse baskets showing my new design;

FIG. 16 is a top plan view of the grid pattern for sink grids and rinse baskets shown in FIG. 15;

FIG. 17 is a bottom view of the grid pattern for sink grids and rinse baskets shown in FIG. 15;

FIG. 18 is a front elevational view of the grid pattern for sink grids and rinse baskets shown in FIG. 15;

FIG. 19 is a rear elevational view of the grid pattern for sink grids and rinse baskets shown in FIG. 15;

FIG. 20 is a left elevational side view of the grid pattern for sink grids and rinse baskets shown in FIG. 15; and,

FIG. 21 is a right elevational side view of the grid pattern for sink grids and rinse baskets shown in FIG. 15.

The broken lines are for illustration purposes only and form no part of the claimed design.
